UNITED STATES PATENT OFFICE.

HAMPTON W. EVANS, OF PHILADELPHIA, PENNSYLVANIA.

COMBINED CENTER, T, AND TRY SQUARE, BEVEL, AND CLINOMETER.

SPECIFICATION forming part of Letters Patent No. 380,714, dated April 10, 1888.

Application filed November 29, 1887. Serial No. 256,373. (No model.)

To all whom it may concern:

Be it known that I, HAMPTON W. EVANS, a citizen of the United States, residing at the city of Philadelphia, in the county of Philadelphia and State of Pennsylvania, have invented certain new and useful Improvements in Universal Squares, of which the following is a specification.

The principal object of my invention is to provide an instrument or device that may be readily adjusted to any angle desired and provided with removable means, whereby said instrument may be used as a center-square as well as a miter-square, try-square, graduated bevel, clinometer, T-square, &c.

My invention consists of an instrument or device constructed substantially in the manner hereinafter described.

The nature of my invention will be fully understood by reference to the accompanying drawings, wherein I have illustrated the same in forms in which it is capable of performing certain functions, and in which—

Figure 1 represents perspectively the several parts detached constituting my improved device. Fig. 2 is a plan or top view of the instrument when used as a center-square. Fig. 3 is a transverse section through the hinge-joint of the device, and also showing the means for clamping the graduated rule to said device and adjusting the same to any desired angle for performing its several functions or uses. Fig. 4 is a top or plan view of the instrument when used as a try-square, and also indicating in dotted lines the use thereof as a miter-square. Fig. 5 is a perspective view of the device when used as a clinometer; and Fig. 6 is a similar view of the device, showing its application as a graduated bevel.

Referring to the drawings for a further description of my invention, A and A' are two triangular-shaped metallic pieces. These two pieces are hinged together in the manner to be presently described, and form what is termed the "head" or "stock" of the device. These triangular-shaped pieces A and A' are provided with cheeks a and a', and at their rear extremities are formed right-angular shoulders a² and a³. The triangular-shaped piece A on the bottom is provided with a narrow flange or rim, a⁴, extending along the inner edge from

the outer extremity to about the middle of the inner edge of this metallic piece A and terminating in an acute angular projection having an adjusting-screw, k, mounted therein. 53

To the inner side of the cheek a is formed a projection or shoulder, a⁵, having an adjusting-screw, a¹⁷, therein. Contiguous to the shoulder a⁵ is a curved seat, a⁶, with a threaded opening, a⁸, located centrally therein, and contiguous thereto is a small opening, a⁷, for the reception of one of the free extremities of a coiled spring, a⁹, through which a screw, a¹⁰, is inserted for holding a clamping-plate, a¹⁰, in proper position above said curved seat a⁶. 65 The rear extremity of the piece A is formed in the shape of a disk, A², with a recessed opening, a¹⁶, therein, as shown in Fig. 3, for receiving a washer, a¹¹, fitted to a stud, b³, cut away to receive it in a manner to be presently 70 fully described.

The triangular-shaped metallic piece A' is provided with an outer cheek, a', and terminating in a right-angular shoulder, a³, and this piece A' has on its inner edge a flange or rim, 75 a¹², extending from the outer extremity to about the middle of the edge of the piece A' and terminating in an angular projection, a¹³. The cheek a' of this piece A' is cut away near its rear extremity, at an angle of forty-five degrees thereto, with an inner angular projection, a¹⁴, as shown in Fig. 1, and in this angular projection is inserted an adjusting-screw, l. The triangular-shaped piece A' beneath the cheek a' has formed therein an oblong opening for 85 the reception of a glass bulb, B, and in the cheek and side of the piece A' are provided oblong openings b and b' for observing the spirit level or bulb. The rear extremity of the piece A' has formed therewith a disk, A³, with a recessed opening, a¹⁵, therein for the reception 90 of a stud, b³, having formed, preferably integral therewith, an enlarged shouldered head, b², with two or more openings, b¹. This stud b³ has its lower portion cut away to receive a 95 metallic or other suitable washer, a¹¹, conforming to the shape of the lower portion of the stud b³, and when secured to place for permitting this stud provided with a threaded shank, b⁵, carrying a nut, to turn freely in the recessed 100 openings a¹⁵ and a¹⁶ of the disks A² and A³.

The two triangular-shaped pieces A and A'

being placed in their normal position, a light washer, of metal or other material, may be placed between the two disks A^2 and A^3 , and the stud b^3 , carrying the shouldered head b^2 , inserted 5 through the openings a^{15} and a^{16} . A washer, a^{11} , is then fitted onto the lower portion of said stud, and a nut, b^6 , screwed onto the threaded shank b^5 thereof until this nut rests snugly up against said washer a^{11} . A semicircular clamp- 10 ing-plate, c , having two or more dowels, c' , is now mounted in the shouldered head, with the dowels c' thereof fitting into the openings b^4 , provided to receive them in said head b^2 , and this plate, tightened and loosened by means of 15 a thumb-screw, c^2 , passing through said plate into the shouldered head. This semicircular clamping-plate c is preferably provided with beveled-off edges and a depending rib or lip, c^3 , in the under surface thereof. The enlarged 20 circular head b^2 , formed with the stud b^3 , is cut away from the center line to the outer periphery thereof for the reception of a graduated rule, D , having a central longitudinal concave groove therein. In this groove the lip or rib 25 c^3 of the semicircular clamping-plate c is made to engage for holding the rule firmly up against the center line or edge of the shouldered head b^2 .

The disks A^2 and A^3 , formed integral with the two-part head or stock, project beyond 30 the shoulders a^2 and a^3 of the cheeks a and a' of the device, the periphery of each of which is graduated, preferably, from zero to ninety degrees, whereby the two-part stock may be readily set at any angle desired, and when secured the screw a^9 may be tightened, thereby 35 forcing the curved plate a^{10} down snugly onto the shouldered head b^2 of the stud, and clamping and firmly holding the same, together with the rule D , in the desired position for use, and 40 allowing as well the free handling of the device.

Having thus described the construction of my improved device, I will now point out more particularly some of the particular features and the several uses thereof. 45

In Fig. 2 I have shown my improved device in application as a center-square, in which the inner edges of each of the triangular-shaped pieces A and A' , forming the 50 stock or head of the device, are arranged in contact with a cylindrical body, H , the center of which is to be ascertained. The graduated rule D is then placed between the shouldered head b^2 and clamp-plate c , and held firmly in 55 position by means of the thumb-screw c^2 , and with the rule in the position as shown in Fig. 2, the true center of the cylindrical body H may then be readily ascertained.

In Fig. 4 I have illustrated my invention in 60 application as a try-square, in which the blade or rule is readily clamped, as shown, in a position at a right angle to the respective cheeks a and a' of the device, and the screw a^{17} , in the right-angular shoulder a^2 of the triangular-shaped piece A , serves as a means for adjusting the blade or rule D at all times to the

proper angle to the device—that is to say, at a right angle to the respective cheeks thereof. With the graduated rule or blade D in the position indicated in Fig. 4, and with the 70 spirit level or bulb in the triangular-shaped piece A , a convenient or handy plumb is presented for use. By merely moving the graduated blade or rule D to an angle of forty-five degrees to the device, so that one edge of the 75 blade rests against the adjusting-screw l in the angular projection a^{14} of the metallic piece A' , a handy and convenient miter-square is formed for use.

By removing the blade or rule D from the 80 clamping mechanism of the device, the instrument may be used as a level, the set-screw k serving to hold the two triangular-shaped metallic pieces A and A' in such a position at 85 all times as that the respective cheeks a and a' thereof will be parallel to each other.

In Fig. 5 I have illustrated my invention in application as a clinometer for readily ascertaining the degrees of inclined planes. My improved device or instrument may be readily 90 arranged for performing this function by placing the triangular-shaped metallic piece A with its cheek a upon the incline and causing the opposite metallic piece, A' , to assume a horizontal position, and then reading off the 95 degrees from the graduated peripheries of the respective disks A^2 and A^3 of the device for quickly ascertaining the angle of the incline to the horizontal plane of the device, whereby a 100 convenient clinometer is presented for such purposes.

In Fig. 6 I have illustrated my improved device in contact with a rectangular-shaped bar, P , showing its application as a graduated bevel. On the peripheral edge of the shouldered head b^2 is indicated a zero-mark, which is arranged at a right angle to the center line, b' , of the shouldered head b^2 . The graduated rule or blade D having been clamped between the shouldered head b^2 and the clamp-plate c 110 by means of the thumb-screw c^2 , it is then moved by hand until the zero-mark on the edge or periphery of the shouldered head b^2 is in line with the mark of the degree desired and as indicated on the periphery of the disk A^3 115 of the triangular-shaped metallic piece A' , when, by simply placing the device up against the rectangular-shaped bar P , a graduated bevel is presented for use.

With the blade or rule D in the position 120 above described, by simply moving the triangular-shaped piece A around on its stud one hundred and eighty degrees the blade D will be brought against the set-screw a^{17} , thereby forming the device into a convenient T-square. 125

It will be observed that the blade or rule D may be used on either one side or the other of the two-part stock or head of the device by simply reversing the stud with its threaded shank and nut and mechanism for clamping the 130 blade or rule to position for use, which may be advantageous in some cases, but I give prefer-

ence to the use of the rule in connection with the two-part stock or head, in the manner hereinabove fully explained.

Having thus described the nature and objects of my invention, what I claim as new, and desire to secure by Letters Patent, is--

1. The herein-described device, consisting of two triangular-shaped metallic pieces pivoted together, and a blade or rule held in position between a shouldered head and plate, substantially as and for the purposes set forth.

2. The herein-described device, consisting of two triangular-shaped pieces pivoted to each other and forming the stock or head thereof, a clamp-plate held in position in a shouldered head carried by the stud forming the pivotal connection of said pieces, and a blade or rule held between said clamp-plate and shouldered head by means of a thumb-screw, substantially as and for the purposes set forth.

3. The herein-described device, consisting of two triangular-shaped pieces pivoted together and forming the stock or head of the device, a clamp-plate held in position in a shouldered plate formed integral with a stud having a threaded shank to which a washer and nut are attached, and said means forming the pivotal connection of said two-part head, and a blade held between said shouldered plate and plate by means of a thumb-screw, substantially as and for the purposes set forth.

4. The herein-described device, consisting of a triangular-shaped two-part head or stock with disks having recessed openings therein, a clamp-plate held in position in a shouldered plate formed integral with a stud having the lower portion thereof partially cut away, and a threaded shank to which is attached a washer and nut, and arranged so as to form the pivotal connection of said two-part head, a blade held in position between said shouldered plate and plate by means of a thumb-screw, substantially as and for the purposes set forth.

5. The herein-described device, consisting of

two triangular-shaped metallic pieces with disks having recessed openings therein, means for pivoting the two metallic pieces together, a graduated blade, and means, as described, for holding the same in position, a seat formed integral with one of the triangular-shaped pieces, and a screw carrying a plate held in position by means of a spring interposed between said plate and seat, substantially as and for the purposes set forth.

6. The herein-described device, consisting of two triangular-shaped metallic pieces provided with cheeks and graduated disks having recessed openings therein, means forming the pivotal connection of said metallic pieces, a clamp-plate and thumb-screw, a blade held in position between said clamp-plate and the shouldered plate of the pivotal connection, and means, as described, in the projections or flanges of said triangular-shaped pieces, whereby said blade may be held in proper adjustment or position, substantially as and for the purposes set forth.

7. The herein-described device, consisting of two triangular-shaped metallic pieces with cheeks, and having in one of said pieces a bulb, and formed integral with said pieces are two partially-graduated disks with recessed openings therein, a shouldered head provided with a stud partially cut away, and with a threaded shank fitting into the recessed openings of said disks, a washer and nut attached to said stud and the threaded shank thereof, a clamp-plate with a turned-down lip held in said shouldered head, a thumb screw fitting into said plate and head, and a blade held in position thereby but free to turn on said pivotal connection to any angle or position to the device, substantially as and for the purposes set forth.

HAMPTON W. EVANS.
